COMBINED BILLFOLD AND CHANGE PURSE

Ernest E. Koch, Forest Hills, N. Y.

Application January 12, 1950, Serial No. 138,087

3 Claims. (Cl. 150—35)

1

This invention relates to purses and aims to provide an improved combined billfold and change purse.

The combined billfold and change purse which I have invented is particularly designed for use by ladies. It is of the type in which the dimensions of the billfold are such that paper currency can be placed in it without folding. The billfold is made of a flexible material such as leather so that it can be folded to bring the bottom edge into alignment with the top edge. Flat paper money is placed in the billfold when it is unfolded and it is then folded and any one of several bills can be withdrawn therefrom without unfolding. The change purse consists of a pocket for coins and the like which is attached to the billfold and which may be opened without unfolding the billfold.

The purses which have been used in the past to provide a combined billfold and change purse have been subject to the serious disadvantage that the billfold contained only a single compartment for the reception of unfolded banknotes and one or more of the following additional disadvantages: the banknote compartment and the coin pocket were not effectively separated from each other; the construction of the banknote compartment has been such that it did not permit ready inspection of the contents of that compartment; inspection of the contents of the banknote compartment required such an exposure of those contents that onlookers could observe them; it was difficult to withdraw only the selected one of a number of banknotes; and they have been of an undesirably bulky construction.

I have discovered that each of the foregoing disadvantages can be overcome and a combined billfold and change purse having a very attractive appearance can be produced by providing the billfold with a mouth which may be closed by a pair of hinged jaws and by mounting the change purse within the mouth of the billfold so that it is concealed when the mouth of the billfold is closed and access may be had to the interior of the billfold along either side of the change purse when the mouth of the billfold is opened.

A combined billfold and change purse constructed in accordance with my invention includes a pair of rectangular walls formed from

2

strips of flexible material fastened to each other along a side edge and the lower edge to provide a banknote container having an opening along one side terminating at its upper end in a wide mouth. A pair of hinged jaws which extend along and are fastened respectively to the upper ends of the walls provides a closure for the mouth of the billfold. The change purse consists of a pocket of flexible material whose mouth can be closed by a pair of hinged jaws which are attached thereto. The change purse is supported within the mouth of the billfold by a pair of stub shafts connecting the ends of the change purse jaws with the corresponding ends of the billfold jaws so that banknotes may be withdrawn from the mouth of the billfold at either side of the change purse. A partition formed from a strip of flexible material preferably extends between the walls of the billfold from their lower ends to the change purse to provide a pair of separated banknote compartments within the billfold and which are accessible through the mouth of the billfold.

A specific embodiment of my invention, in the form which I now prefer, is illustrated in the accompanying drawings in which:

Fig. 1 is an elevation of one face of the folded purse;

Fig. 2 is an elevation of the other face of the folded purse;

Fig. 3 is an elevation of the inner side of the unfolded purse;

Fig. 4 is a side elevation of the unfolded purse showing the billfold mouth in open position and the billfold walls spread apart;

Fig. 5 is an enlarged transverse section of the unfolded purse;

Fig. 6 is a section along the lines 6—6 of Fig. 5;

Fig. 7 is a top plan view of the purse showing the hinged jaws of the billfold mouth in open position;

Fig. 8 is a view similar to Fig. 7 but showing the hinged jaws of the mouth of the change purse in open position;

Fig. 9 is a plan view of the purse showing the mouth of the billfold in closed position; and

Fig. 10 is a side elevation showing the jaws of the billfold mouth and the jaws of the mouth of the change purse in open position.

The purse illustrated in the drawings includes a rectangular outer wall 14 and a rectangular inner wall 15. The outer wall 14 is formed from a strip 16 of flexible material such as leather and is preferably lined with a strip 17 of material such as silk. The inner wall 15 is preferably formed from a strip 19 of flexible material such as leather lined with a strip 20 of material such as silk. The walls 14, 15 are attached to each other along one of their side edges and along their bottom edge to provide a container which is open along one side, for banknotes 21. The upper ends of the walls 14, 15 are attached respectively to hinged jaws 22, 23 which provide a closure for the wide mouth of the banknote container. A pair of clasps 24, 25 are attached to the respective jaws 22, 23 and are adapted to engage each other when the mouth of the banknote container is closed.

A change purse 27 is formed from a folded strip 28 of flexible material such as leather whose ends are attached to hinged jaws 29, 30. Clasps 31, 32 are attached to the jaws 29, 30 and are adapted to engage each other when the mouth of the change purse 27 is closed. The dimensions of the change purse 27 are such that it may be contained between the upper portions of the walls 14, 15 when the jaws 22, 23 are closed and it is supported in this position by a pair of stub shafts 33, 34 which connect the ends of the pair of jaws 29, 30 with the corresponding ends of the pair of jaws 22, 23 so that both pairs of jaws are hinged along a common axis.

A partition 36 between the walls 14, 15 divides the space between those walls into two separated compartments 37, 38 for the reception of unfolded banknotes. The partition 36 is preferably formed from two strips 39, 40 of a flexible material such as silk. The upper end of the partition 36 is connected with the change purse 27, and, in the specific embodiment of my invention which is shown in the drawings, the strips 39, 40 embrace the pocket of the change purse 27 and have their upper ends connected with the jaws 29, 30 as best illustrated in Fig. 5. The lower ends of the strips 39, 40 are fastened to the lower ends of the walls 14, 15.

The bottom of the change purse 27 is above the middle of the billfold. This permits the billfold to be folded without interference from pocket 15 or its contents, and the bottom edge of the billfold can be brought into alignment with its upper edge. The inner wall 15 is provided with a snap fastener 42 to keep the billfold in folded position. The inner wall 15 may also be provided, if desired, with a pocket 43 for calling cards, identification cards, and the like.

Banknotes, checks, and the like, can be placed in the compartments 37, 38 when the billfold is unfolded and the billfold walls 14, 15 are spread apart as best illustrated in Fig. 4. The provision of a pair of separated compartments 37, 38 enables the user to place bills of large denominations in one of the compartments and bills of smaller denominations in the other compartment. After the billfold has been folded, the contents of the compartment 37 or the compartment 38 can be very easily examined by releasing the clasps 24, 25 and swinging the jaws 22, 23 apart. This provides a very wide mouth through which any selected bill can be withdrawn from the compartment 37 or the compartment 38 without removing any other bills from that compartment, and the change purse 27 may be swung about the stub shafts 33, 34 to hide the contents of either

of the compartments 37 or 38 so that, when the user desires to extract a bill of small denomination from one of the compartments, she need not disclose to others the presence of bills of larger denominations in the other compartment.

After the jaws 22, 23 are swung apart, the change purse can be easily opened by releasing clasps 31, 32 and swinging apart jaws 29, 30. Since the jaws 22, 23 and the jaws 29, 30 are hinged along a common axis, both pairs of jaws may be opened to the same extent and the likelihood of misplacing coins in the banknote compartment may be avoided thereby. Engagement of the clasps 31, 32 prevents coins from spilling into the billfold when the purse 27 is closed.

The terms which I have used in describing the preferred embodiment of my invention which is illustrated in the drawings are terms of description and not of limitation, and it is to be understood that modifications can be made in the specific embodiment of my invention which I have described without departing from the spirit of my invention as it is defined in the following claims.

What I claim is:

1. A combined billfold and change purse comprising a pair of rectangular walls formed from strips of flexible material fastened to each other along a side edge and a lower edge, a partition of flexible material between said walls and fastened thereto along said lower edge to provide a pair of banknote compartments communicating with a wide mouth, and a closure for said mouth comprising a pair of hinged jaws extending along and fastened respectively to the upper ends of said walls; a pocket formed from flexible material contained within said mouth, connected with the upper end of said partition and having an open end accessible through said mouth, and a closure for said open end comprising a pair of hinged jaws attached thereto; and a pair of stub shafts connecting the ends of the first-named pair of jaws with the corresponding ends of the second-named pair of jaws.

2. A combined billfold and change purse comprising a pair of rectangular walls formed from strips of flexible material fastened to each other along a side edge and a lower edge, a partition between said walls formed from a pair of strips of flexible material fastened to said walls along their lower edges to provide a pair of banknote compartments communicating with a wide mouth, and a closure for said mouth comprising a pair of hinged jaws extending along and fastened respectively to the upper ends of said walls; a pocket formed from flexible material contained within said mouth between the upper portions of the partition strips and having an open end accessible through said mouth, and a closure for said open end comprising a pair of hinged jaws attached thereto; and a pair of stub shafts connecting the ends of the first-named pair of jaws with the corresponding ends of the second-named pair of jaws.

3. A combined billfold and change purse comprising a pair of rectangular walls formed from strips of flexible material having a pair of side edges and a lower edge fastened to each other along one side edge and the lower edge, a partition of flexible material between said walls and fastened thereto along said lower edge to provide a pair of separated banknote compartments each having an opening along the other of said side edges and communicating with a wide mouth, and a closure for said mouth comprising a pair

of hinged jaws extending along and fastened respectively to the upper ends of said walls; a pocket formed from flexible material contained within said mouth, connected with the upper end of said partition and having an open end accessible through said mouth, and a closure for said open end comprising a pair of hinged jaws attached thereto; and a pair of stub shafts connecting the ends of the first-named pair of jaws with the corresponding ends of the second-named pair of jaws.
